Inventor

J. Rankin

J. E. PARKER, OF WEST MERIDEN, CONNECTICUT.

Design No. 3,318, dated January 5, 1869.

DESIGN FOR A SHELF-BRACKET.

The Schedule referred to in these Letters Patent and making part of the same.

To all whom it may concern:

Be it known that I, J. E. PARKER, of West Meriden, county of New Haven, and State of Connecticut, have invented a certain new and useful Design for Shelf-Bracket; and, to enable others skilled in the art to make and use the same, I will proceed to describe its construction, referring to the illustrations, in which the same letters indicate like parts in each of the figures.

In the accompanying photographic illustrations is shown a side view.

a is a wall-plate; *b* is a shelf-support; *c* is primitive

ornamental frame-work, embellished by depressions and elevations, *d e*, interspersed with decorative braces, *f*; the whole combined, to produce a highly-ornamental shelf-bracket, substantially as shown and described.

What I claim, and desire to secure by Letters Patent, is—

The design for a shelf-bracket, as illustrated and described.

J. E. PARKER. [L. S.]
